Attorney

UNITED STATES PATENT OFFICE.

ROSS N. CLANIN, OF WHITING, INDIANA.

DOOR-FASTENING.

1,385,814.

Specification of Letters Patent. Patented July 26, 1921.

Application filed June 30, 1920. Serial No. 393,071.

To all whom it may concern:

Be it known that I, Ross N. CLANIN, citizen of the United States, residing at Whiting, in the county of Lake and State of Indiana, have invented certain new and useful Improvements in Door-Fastenings, of which the following is a specification.

My invention relates to door fastenings, and particularly to hinges, hasps, and like door hardware intended for mounting and securing doors in place.

An object is to provide a fastening including a plate having a screw to be turned into a door or adjacent jamb to secure the plate in place, and in constructing a portion of the plate to retain the parts against being turned to withdraw the screw.

A further object resides in constructing the fastening in two parts, one of which is to be secured on the door and the other upon the jamb adjacent thereto, which parts are to be connected together.

With these and other objects in view which will be apparent from the drawings, specification and claims, this invention includes certain novel features of construction and combinations of parts which will now be set forth.

In the drawings:

Figure 1 is a view in perspective showing a hasp and staple constructed in accordance with my invention as they appear when mounted in position for use.

Fig. 2 is a top plan view of the members illustrated in Fig. 1 to better show the construction thereof.

Fig. 3 is a front elevation of a hinge made according to my invention.

Fig. 4 is a top plan view of the hinge.

Fig. 5 is a fragmentary detail view of one of the base plates.

Fig. 6 is a fragmentary perspective view showing the position of the parts when the plate is secured in place.

In the embodiment of my invention with a hasp structure a base plate 1 is provided for the staple and a base plate 2 for the hasp member. The staple 3 is secured on the face of the plate 1 and hasp member 4 is hinged at one end of base plate 2. The remaining end of plate 2 and both ends of plate 1 are cut or shaped to provide the sharp angles or points 5, substantially as shown in Fig. 5. These points are bent and shaped, as best disclosed in Fig. 2, to provide spurs 6 and 7, on base plate 1 and spur

8 on base plate 2. These spurs are disposed with their points in a plane with or slightly back from the plane of the inner sides of the plates.

A securing screw 9 is carried centrally on the inner side of plate 1 to project therefrom, and a securing screw 10 is similarly located on plate 2.

In the use of this form of my invention plate 1 will be secured upon either the door or door jamb and plate 2 will be secured upon the remaining member. The point of securing screw 9 is made to penetrate the wood of the member on which plate 2 is to be secured and this plate is turned to cause the screw to penetrate. When maximum penetration has been secured and plate 2 is drawn against the door or jamb member the plate is adjusted to properly position staple 3 and hammer blows are directed against spurs 6 and 7. These blows upon the bent ends of the plate cause the spurs to sink into the wood as shown in Fig. 6, and thus the plate is held against being turned to withdraw screw 9. Screw 10 is penetrated in the remaining member at a point that will fit staple 3 and plate 2 is revolved to turn screw 10 into the wood. When plate 2 is tightened into place spur 8 is driven into the wood to guard against movement of the same.

In Figs. 3 and 4 I have shown application of the invention in conjunction with a strap hinge. The plate members 11 and 12 have ends bent and shaped into interfitting bearing portions adapted to receive a loose butt 13, the outer ends of the plates being shaped as shown in Fig. 5, and being bent to provide spurs 14 and 15. Plate 11 has a screw 16 on the inner side thereof and a screw 17 is provided on plate 12.

In mounting the hinge in place the butt 13 is removed and the two plates may then be revolved to turn screws 16 and 17 into the wood of a door and jamb to secure the plates in place, spurs 14 and 15 being driven into the wood to retain these plates against movement to dislodge the bearing portions or to loosen the securing screws. The bearing portions are then fitted together and butt 13 is inserted through the aligned openings thereof. If desired this loose butt can be headed over at its lower end to prevent removal.

While, in the foregoing, I have described specific embodiments, and have mentioned

only certain possible modifications, it will be appreciated that in practice I do not limit myself to such specific details as herein set forth, but may resort to any practical modifications falling within the scope of the invention as defined in the appended claims.

I claim:

1. A door fastening including a pair of plates one of which is to be mounted on a door and the other upon the adjacent door jamb and the plates to be then connected together, said plates having securing screws projecting on their inner sides and being provided with spur formations bent to have their points in front of the plane of the inner sides of said plates.

2. A door fastening including a mounting plate having a securing screw connected on

and projecting from its inner side to secure 20 the plate in place, said plate having a spur thereon to be driven into the wood penetrated by said screw to hold the base plate against turning movement.

3. A door fastening in the form of a 25 hinge including a pair of base plates provided with interfitting bearing portions and having their outer extremities made pointed and bent to provide spurs having their ends outside of a plane including the 30 inner faces of said plates, a securing screw connected with each of said plates to project from the inner face, and a butt to be fitted through the bearing portions of said plates.

35

In testimony whereof I affix my signature.

ROSS N. CLANIN.
